PACKAGING

Richard B. Rein, Philadelphia, Pa., assignor to Smith Kline & French Laboratories, Philadelphia, Pa., a corporation of Pennsylvania

Filed Nov. 2, 1962, Ser. No. 235,009

1 Claim. (Cl. 206—42)

This invention pertains generally to the field of packaging, and particularly to receptacles capable of being fabricated from cardboard or other paper product, or from a plastic, or other suitable material. The invention pertains more particularly to a receptacle comprised of two elements hinged on one edge, e.g. by cut scoring or crease scoring, said elements having scalloped inner edges which overlap one another to form pockets when said elements are in folded position. The resulting receptacle with the articles to be packaged positioned within said pockets may now be encased in a wrapper or envelope of any desired type.

Two element receptacles of this general character are known in the art, but are of an entirely different configuration in that the pockets are formed by punching or otherwise cutting material from each of said elements to form void spaces or windows therein which when said elements are in folded position fall into alignment to constitute said pockets.

The material thus cut away in the formation of the void spaces or windows is useless for other purposes and goes into scrap. This represents a loss of considerable significance moneywise, particularly when such receptacles are made in large quantity which is frequently the case. Moreover, the problems inherent in rather large scale waste disposal are involved, one of which is the cost of labor in collecting and handling of such waste.

A feature of the invention resides in a receptacle of a configuration such that the desired pockets are provided without loss of material in affording the same.

A further feature of the invention resides in the production of a plurality of receptacles with minimum increase in consumption of material over that required to produce a single receptacle having cut out voids or windows.

Additional features of the invention will become apparent to persons skilled in the art as the specification proceeds in connection with the accompanying drawings in which:

FIGURE 1 is a plan view illustrating the production in accordance with the invention of two receptacles without loss of material for affording pockets;

FIGURE 2 is a plan view of a receptacle of the invention in open position with objects inserted;

FIGURE 3 is a plan view of the receptacle of FIGURE 2 in closed position with objects inserted; and

FIGURE 4 is a perspective view illustrating the encasement of a closed receptacle in a wrapper.

Referring now more particularly to FIGURE 1, at 11 is shown a sheet of material from which two receptacles are to be made, without loss of material in affording the desired pockets.

For better illustration, receptacle 12 is shown shaded, and receptacle 13 without shading.

To produce receptacles 12 and 13, sheet 11 is cut all the way through by any suitable means along each of the full lines shown within its borders. Otherwise considered, these lines may be regarded as a single line having a straight portion 14, a straight portion 15 at a right angle to portion 14, a wavy portion 16 forming scallops 17 and 18 on receptacles 12 and 13, respectively, a straight portion 21, a straight portion 22 at a right angle to portion 21, a straight portion 23 at a right angle to

2

portion 22, a wavy portion 24 forming scallops 25 and 26 on receptacles 12 and 13, respectively, a straight portion 27, and finally, a straight portion 28 at a right angle to portion 27.

Usually, but not necessarily, diagonal corners 31 and 32, shown in dotted lines, are cut away so as to bring edge 33 on receptacle 13 in alignment with its edge 34 resulting from cutting along line portion 27, and so as to bring edge 35 on receptacle 12 in alignment with its edge 36 resulting from cutting along line portion 15. The result is that when receptacle 13 is in folded position, edge 33 will be flush with edge 34, and likewise when receptacle 12 is in folded position, edge 35 will be flush with edge 36.

In addition and to facilitate folding, receptacle 12 is usually provided, depending upon the thickness of sheet 11, with either a crease score or a cut score 41, shown for convenience in a dotted line, between its elements 42 and 43, and receptacle 13 with a similar score 44, also shown for convenience in a dotted line, between its elements 45 and 46.

Thus receptacle 12 may be regarded as being hinged at 41, and receptacle 13 at 44.

Crease scoring and cut scoring are terms well known in the art, the result of crease scoring being a crease which is sufficient for hinging in the case of lighter weight sheets, whereas the result of cut scoring is a severance of the material of the sheet part way therethrough which is more convenient for hinging in the case of heavier weight rigid sheets.

The cutting along the full lines shown in FIGURE 1 and the scoring along dotted lines 41 and 44 may be done by hand with any suitable tool or tools such as a knife, scissors, and/or the hand tools employed in the carving of wood or the tooling of leather. In large scale production, however, this is done by stamping with a die made to cut and score respectively in accordance with the above description, the construction and operation of which will become so apparent to persons skilled in the art upon becoming familiar with the invention as not to require further description. For convenience in further description, scoring will be considered as being applied to the upper face of sheet 11 as seen in FIGURE 1.

Thus, a method has been provided for making packaging receptacles wherein a sheet of material, e.g. sheet 11 as seen in FIGURE 1, is cut intermediate at borders along a pair of laterally spaced wavy lines, e.g. lines 16 and 24, to produce contiguous scallops along each said wavy line, e.g. scallops 17 and 18 along line 16, and scallops 25 and 26 along line 24; the scallops produced by cutting along one said wavy line, e.g. line 16, being in general alignment transversely of said wavy lines, i.e. vertically as seen in FIGURE 1, with the scallops produced by cutting along the other of said wavy lines, e.g. line 24; cutting said sheet intermediate its borders along a third line, i.e. line 22, positioned laterally to and intermediately of said wavy lines; one end of said third line cutting connected by cutting, e.g. along line 21, to the adjacent end, e.g. the right end as seen in FIGURE 1, of one of said wavy lines, e.g. line 16; the other end of said third line cutting connected by cutting, e.g. along line 23, to the adjacent end, e.g. the left end as seen in FIGURE 1, of the other of said wavy lines, e.g. line 24; cutting along a fourth line, e.g. line 14, spaced laterally outwardly from one of said wavy lines, e.g. line 16, from the edge of said sheet, e.g. the right edge of sheet 11 as seen in FIGURE 1 adjacent the connection, e.g. by cutting along line 21, of said third line cutting with an end of said last-mentioned wavy line; said fourth line cutting terminating short of the opposite edge of said sheet, e.g. the left edge of sheet 11 as seen in FIGURE 1, and connected by cutting, e.g. along line 15, to the other end of

said last-mentioned wavy line; and cutting along a fifth line, e.g. line 28, spaced laterally outwardly from the other of said wavy lines, e.g. line 24, from the edge of said sheet, e.g. the left edge of sheet 11 as seen in FIGURE 1, adjacent the connection, e.g. by cutting along line 23, of said third line with an end of said last-mentioned wavy line, said fifth line cutting terminating short of the opposite edge of said sheet, e.g. the right edge of sheet 11 as seen in FIGURE 1, and connected by cutting, e.g. along line 27, to the other end of said last-mentioned wavy line. In addition, scoring along dotted lines 41 and 44 is preferable, as is the elimination of the diagonal corners 31 and 32 for reasons above given.

In FIGURE 2, receptacle 12 is shown separated from receptacle 13, with its lower face in FIGURE 1 becoming its upper face in FIGURE 2. This puts score 41 to the rear in FIGURE 2.

It will be seen from FIGURE 2 that elements 42 and 43 are similarly shaped, and that they might in fact be made identical, although this is by no means essential. Each consists of laterally spaced members 51 and 52, the former having scallops on its inner edge projecting toward the latter, members 51 and 52 being joined by an end bar 54. To form the receptacle, the outer longitudinal edge of the scalloped members of 51 of one element is hinged to the outer longitudinal edge of the non-scalloped member 52 of the other element. As seen in FIGURE 2, it will be noted that member 51 of element 43 is hinged on its outer edge at 41 to the outer edge of member 52 of element 42.

When packaging relatively small objects, such as capsules, ampoules, pills and the like, it is convenient, although not strictly essential, to encase them between thin sheets of material with the objects so spaced as to fit into the pockets. This is illustrated in FIGURES 2 and 3 wherein capsules 55 are positioned in pockets 56 (FIGURE 3) by virtue of being encased in appropriate spaced relation in transparent encasement 57 shown crinkled at 58.

To close receptacle 12 from its open position as seen in FIGURE 2, its element 42 is brought forward and down onto its element 43 as illustrated in FIGURE 3, wherein it will be noted that the scallops on element 42 overlap the scallops on element 43 to complete the formation of pockets 56 in which capsules 55 are visible due to the transparent character of encasement 57, the latter being engaged between pockets 56 by the overlapping scallops.

Receptacle 12 may be held in closed position by any suitable means, such as by a small piece of adhesive tape binding its free edges together, but for large scale merchandizing it is preferable to encase the receptacle in a suitable wrapper, such as open-ended wrapper 61 shown in FIGURE 4 with receptacle 12 partially inserted therein endwise. It is also preferable to provide wrapper 61 with a cut out or window 62 through which, when the receptacle is fully inserted, one of the capsules, or other object being packaged, may be seen.

While receptacle 12 (and the same applies to receptacle 13) has been shown as having three pockets, it is to be understood that any number of pockets may be provided, that is one or more.

Also while encasing the objects in spaced relation, such as in an encasement 57, is preferred, the object or objects may be individually inserted in the pocket or pockets

and held in position by any other means, such as by wrapper 61, window 62, if employed, being such as not to permit loss.

Also while scoring to provide a hinge is preferred, the hinge may be provided by other means, such as by a strip of tape overlapping the adjoining edges of the two elements.

Then too, the periphery of the receptacle, with its elements hinged together, may have any other configuration than that afforded by straight lines as will be obvious to persons skilled in the art upon becoming familiar with the invention.

Also, while a bar 54 for joining members 51 and 52 (or their equivalent) at only one of the adjacent ends thereof has been shown and described, a similar bar may also be provided at the other of their adjacent ends, if desired for any reason.

Then too, while the material from which the receptacles are made is generally flat on both sides, and may be of any desired thickness, deviation is permissible, particularly for decorative or other purposes, such as embossing an outer surface or surfaces of the receptacle, or an even an inner surface or surfaces.

Therefore, it is to be understood that the above particular description is by way of illustration and not of limitation, and that changes, omissions, additions, substitutions and/or other modifications may be made without departing from the spirit of the invention. Accordingly, it is intended that the patent shall cover, by suitable expression in the claim, the various features of patentable novelty residing in the invention.

What is claimed is:

A packaging receptacle comprising two elements connected together in folding arrangements, each said element having a pair of laterally spaced members joined together and a scalloped edge defining a plurality of scallops on one of said members projecting toward the other of said members in the space therebetween, the connection between said elements being by hinging means comprising a score joining the outer longitudinal edge of the scalloped edge member of one element to the outer longitudinal edge of the other member of the other element, and the longitudinal arrangement of said elements relative to each other and the position of the scallops thereon being such that the scallops of one element overlap the scallops of the other element when said receptacle is in closed position thereby forming a plurality of spaced object receiving pockets between the overlapping scallops, a thin flat encasement positioned between the elements of said receptacle when in closed position, a plurality of objects within said encasement, said encasement holding said objects in spaced relation conforming to the spacing between the pockets in said receptacle with said objects positioned in said pockets, and an open-ended wrapper enclosing the receptacle.
